US00D880289S

(12) **United States Design Patent** (10) Patent No.: **US D880,289 S**
(45) Date of Patent: ** Apr. 7, 2020

(54) **SINGLE-SERVE BEVERAGE CAPSULE**

(71) Applicant: **GRUPPO GIMOKA S.r.l.**, Trezzano sul Naviglio (IT)

(72) Inventor: **Massimiliano Valsecchi**, Trezzano sul Naviglio (IT)

(73) Assignee: **GRUPPO GIMOKA S.r.l.**, Trezzano sul Naviglio (IT)

(**) Term: **15 Years**

(21) Appl. No.: **29/703,644**

(22) Filed: **Aug. 28, 2019**

Related U.S. Application Data

(62) Division of application No. 29/621,941, filed on Oct. 12, 2017, now Pat. No. Des. 864,707.
